(57) **CLAIM**

The ornamental design for a toothed broom block, as shown and described.

DESCRIPTION

FIG. 1 is a perspective view of the toothed broom block of the subject invention;

FIG. 2 is a front view of the toothed broom block of the subject invention;

FIG. 3 is a rear view of the toothed broom block of FIG. 1;
FIG. 4 is a left view of the toothed broom block of FIG. 1;
FIG. 5 is a right view of the toothed broom block of FIG. 1;
FIG. 6 is a top plan view of the toothed broom block of FIG. 1; and,

FIG. 7 is a bottom view of the toothed broom block of FIG. 1.

The broken line showing of a handle in FIG. 1 is included for illustrative purposes only and forms no part of the claimed design.
